UNITED STATES PATENT OFFICE.

FREDERICK MAX PORITZ, OF NEW YORK, N. Y., ASSIGNOR TO ARTISTIC BRASS & BRONZE WORKS, INC., OF NEW YORK, N. Y., A CORPORATION OF NEW YORK.

DESIGN FOR A LAMP BASE OR SIMILAR ARTICLE.

Application filed February 11, 1928. Serial No. 25,407. Term of patent 3½ years.

To all whom it may concern:

Be it known that I, FREDERICK MAX PORITZ, a German citizen, and a resident of the borough of Manhattan, city, county, and State of New York, have invented a new, original, and ornamental Design for a Lamp Base or Similar Article, of which the following is a specification, reference being had to the accompanying drawing, forming a part thereof.

Fig. 1 of said drawing shows a plan view of my new design for a lamp base, only a portion of the ornamentation being shown completed, the unornamented portion involving a mere repetition of that portion more fully shown.

Fig. 2 is a side elevational view, only a portion thereof being completed, the unfinished portion involving a mere continuation of that portion more fully shown.

I claim:

The ornamental design for a lamp base or similar article, as shown and described.

FREDERICK MAX PORITZ.
